(57) **CLAIM**

The ornamental design for an agricultural tractor hood, as shown and described.

DESCRIPTION

FIG. 1 is a perspective view of an agricultural tractor hood showing our new design.

FIG. 2 is an elevational view of the agricultural tractor hood design of FIG. 1.

FIG. 3 is an elevational view of the agricultural tractor hood design of FIG. 1.

FIG. 4 is a front view of the agricultural tractor hood design of FIG. 1.

FIG. 5 is a rear view of the agricultural tractor hood design of FIG. 1.

FIG. 6 is a plan view of the agricultural tractor hood design of FIG. 1; and,

FIG. 7 is a bottom view of the agricultural tractor hood design of FIG. 1.

The broken line showing is for illustrative purposes only and forms no part of the claimed design.
